UNITED STATES PATENT OFFICE.

ANDREW STEINBERGER, OF NEW YORK, N. Y.

EXERCISING PRIZE AMUSEMENT DEVICE

Application filed December 22, 1926. Serial No. 156,415.

This invention relates generally to amusement devices used in amusement parks and the like, the invention having more particular reference to an improved type of amusement device.

The invention has for an object the provision of an improved type of amusement device affording muscular exercise and pleasurable pastime.

10 For further comprehension of the invention, and of the objects and advantages thereof, reference will be had to the following description and accompanying drawings, and to the appended claims in which
15 the various novel features of the invention are more particularly set forth.

Fig. 1 of the drawings, is a top plan view of my improved amusement device.

Fig. 2 is a side elevational view thereof.
20 Fig. 3 is a vertical sectional view taken

on the line 3—3 of Fig. 1.
Fig. 4 is an enlarged side elevational view of the rolling cannon as used in connection with my improved device.

25 Fig. 5 is a top plan view thereof.

Fig. 6 is a vertical sectional view taken on the line 6—6 of Fig. 4.

Fig. 7 is a side elevational view of the braking device as used in connection with my improved device.

Fig. 8 is a vertical sectional view taken on the line 8-8 of Fig. 7.

Fig. 9 illustrates the bumper and brake operating device as used in connection with my improved device.

Fig. 10 is a vertical sectional view taken on the line 10—10 of Fig. 9.

Fig. 11 is a side elevational view, partly in section, of the electrical device as used in connection with my improved device.

Fig. 12 is a diagrammatical illustrational view of the electrical circuit comprising a part of the present invention.

As here embodied my improved device
45 comprises briefly a framework consisting of
standards 10, attached at their lower ex-
tremities to the floor, and supported by
cross members 11, adapted to support an
inclined platform 12. The fort 13, pref-
50 erably the replica of the front portion of a
fort, having towers 14, and doorways 15, or
openings formed therein, the fort 13 being
positioned at the extreme upper extremity
of the inclined platform 12. The rails 16,
55 are attached to the inclined platform 12,
the center rails 17, are also attached to the

inclined platform 12, the rails 16 and the center rails 17 extending the entire length of the inclined platform 12, as clearly shown in Figs. 1 and 2. The rails 16 are provided with upper horizontal extended elements 18, adapted to support the wheels 19 of the cannon 20, and are provided with an upper vertical extended extremity 21, so as to hold the wheels 19 rotatively attached to the cannons 20 in contact with the rails 18, when the cannons 20 are pushed up the rails 18. The rollers 22 rotatively supported and attached to the frame work 23 of the cannon 20, and extending therefrom, and are positioned directly below the said extended elements 18 of the rails 17, so as to prevent the cannon from being pushed or forced off the rails 17. Similar rollers 24 are also rotatively attached to the framework 23 of the cannons 20, and extend therefrom, and are positioned directly below the horizontal extended elements 25 of the center rails 16, so as to further support or prevent the cannon 20 from being pushed off the rails 17. The frame work 23 of the cannons 20, extending to the rear thereof, and having attached at its extremity, a handle 26, by means of which the cannons 20 may be pushed up the rails 17. The roller 27 is rotatively attached, at or near the center of the extended portion of the framework 23, and is positioned directly above and in contact with the horizontal extended elements 25 of the center rails 16, so as to further prevent the cannons 20 from being pushed off the rails 17. The bumper member 20' has attached thereto springs 21', superimposed between the bumper member and a support 21^a, positioned so as to cushion the stopping of the said cannons 20.

Referring in particular to Figs. 7, 8 and 9, in which I have illustrated the braking device as used in connection with my improved device, the bar 30 has its extremities formed 100 or bent, slightly curved, as at 31, and is attached to the supports 32, slidably mounted in one of the rails 16, and has attached, at its extended extremities a bar 33. The tension springs 34, are positioned on the supports 32, so as to normally hold the bar 30 in an extended position. The block 35 is pivotally attached, as at 36, to the rail 16, and is positioned directly below the rail 16, between the said rail and the bar 33. The lever 37 is attached to the block 35 and to the operating rod 38, which is pivotally 105 110

attached to the arm 39, which is also pivotally attached to the rail 16. It being understood that a second braking device, similar in construction to the above described braking device, is also attached by a second lever 40 to the operating rod 38, as clearly shown in Fig. 2. The said braking device being positioned or located in any desired place on the said rail 16. The operating rod extends 10 from the said braking devices to the lower extremity of the rail 16, and is pivotally attached, as at 41, to a lever 42, pivotally attached, as at 43, to a bracket 44 attached to the rail 16. The engaging member 45 is attached to the lever 42, and is adapted to engage notches 46 formed in the sector 47, attached to the bracket 44, so as to hold the lever 42 in any desired relative position. The lower extremity 48 positioned in the 20 forward end of the cannon 20 has its forward end 49 pointed, and has attached thereto a shoe 50, having its extremities curved, as at 51. The above described construction being such as will permit the lever 45, when pivoted, to allow the forward end 48 to strike the bar 30, so as to impede the speed of the cannon 20 up the inclined rails 16, it being understood that the said speed may be impeded more or less, as may be desired, by 30 pivoting the said lever 42. It being also understood that the person desiring muscular exercise will push the cannon 20 up the inclined rails 16, and endeavor to cause the cap 50' of the framework 23 of the cannon 35 20, of a common explosive substance, to strike the protruding element 51' attached to the said fort 13, and located inside the doorways 15, so as to explode the cap 50'. It being obvious that the above mentioned 40 described braking devices may be positioned, as herein before described, so as to make it more difficult for the person to accomplish the desired result.

A third braking device, similar to the 45 above described braking devices, has attached thereto a lever 52, attached to the rod 53, which is pivotally attached to the operating rod 53' extending at or near the lower extremity of the rail 16, slidably mounted in a bracket 54, and has attached at its lower extremity a handle 55. The above described construction being such as will permit the said third braking device, to be engaged with the protruding element 50 55 51 of the shoe 50, when the cannon 20 is returning or rolling down the inclined rails 16, so as to impede the speed of the cannon 20, as is required to prevent the cannons 20 from damaging my improved device. It 60 being further understood that the first mentioned braking devices may also be used for the purpose as above set forth.

The dash pot 60, is slidably mounted in the upper extremity of one of the rails 16. 65 The plunger 61 is slidably positioned in the

dash pot 60, and has attached thereto an extended member 75, adapted to slidably engage the cup member 76, which is normally held in an extended position by the expansion spring 77, so as to maintain the engagement of the contact points 78 and 79. The dash pot 60 is attached to the arm 80, hinged as at 81 to the bracket 82 attached to the rails 16. The contact point 78 is connected, by means of an electric wire 62 to the battery 63, and by means of the electric wire 64 to the switch 65, located at the front of my improved device, as clearly shown in Fig. 1. The switch 65, is connected by means of the electric wire 66 to the switch points 67 located in the said fort 13. The battery 63 is connected by the electric wire 68 to the solenoid 69, and by means of the electric wire 68' to the electric bell 71, gong or the like, located in the fort 13. The electric bell 71 is connected by means of the electric wire 72 to the said switch points 67. The solenoid 69 is provided with a movable core 73, having an extended element 74, adapted to complete the above described electric circuits, when the cannons 20 are pushed to the top of the rails 16, so as to ring the said electric bell.

The standards 70, are attached to the platform 12, and extend upward therefrom, and are located at any desired places on the said platform 12, and are provided for the purpose of awarding or giving a prize to the person who pushes the cannons 20 past any one of the said standards 70. It being understood that the main or first prize will be awarded or given to the person pushing the cannons 20 the entire length of the said rails 16, so as to explode the cap 50', and so as to light the said electric light bulbs and ring the said electric bell. It should be understood that the cannons 20 may be forced up the incline from the bottom thereof by a manually applied thrust.

While I have above described the preferred form, construction and arrangement of the several elements employed, it will be understood that the device is, nevertheless, susceptible of considerable modification therein, and I therefore reserve the privilege of resorting to all such changes as may be fairly embodied within the spirit and scope of the invention as claimed.

Having thus described my invention, what I claim as new and desire to protect by Letters Patent of the United States is as follows:

1. In an amusement device of the class described, an inclined platform, inclined rails mounted on said platform, a plurality of spaced apart braking devices mounted on said rails each comprising a bar having its extremities slightly curved downwardly, supports attached to said bar and slidably mounted on said rail, a second bar attached

at its extremities to said supports, springs disposed around said supports and interposed between said rail and said first mentioned bar for normally urging said braking device in an upwardly extended position, a block pivotally mounted on said rail and positioned directly therebelow between the lower surface thereof and said second mentioned bar, a lever pivotally attached at one end to said block, an operative lever operatively mounted on said rails disposed therebelow and pivotally attached to the lower end of said first mentioned lever, said operating lever extending from said braking devices to the lower extremity of said rail, a bracket attached to the lower end portion of said rail comprising a sector having notches thereon, a hand lever pivotally mounted on said bracket and pivotally connected with the lower extremity of said operating lever, engaging means mounted on said hand lever adapted to engage in the notches of said sector for retaining said hand lever and the braking devices operatively connected therewith in a predetermined position of adjustment, and a cannon mounted on said inclined rails comprising a depending brake shoe adapted to engage said braking device for impeding the speed of said cannon up said inclined rails.

2. In an amusement device of the class described, a base comprising an inclined platform, spaced rails mounted on said inclined platform, a cannon comprising spaced traction wheels movably mounted on said rails; a depending braking shoe on said cannon extending below one of said rails at the side thereof, an adjustable braking device slidably mounted on said rails in registration with said braking shoe, and operating mechanism comprising a lever pivotally mounted on said rail and operatively connected with said braking device and extended to the lower end of said rails adapted to adjustably position said braking device relative to the braking shoe of said cannon for suitably impeding the speed of

upward and downward movement thereof.

3. In an amusement device of the class described, a base comprising a platform, spaced rails mounted on said platform comprising longitudinal flanges, a cannon comprising traction wheels mounted on said spaced rails, extensions on said cannon depending below the flanges of said rails, rollers rotatively mounted on said extensions disposed below said flanges for retaining said cannon wheels on said rails, braking shoes on said cannon depending below said rails, adjustable braking mechanism slidably mounted on said flanges comprising a bar adapted to be engaged by said brake shoes, and control means pivotally mounted on said rail and operatively connected with said bar for adjustably positioning said bar, varying the impediment of said cannon as the latter passes over said braking device.

4. In an amusement device of the class described, a base comprising a platform, spaced rails mounted on said platform comprising longitudinal flanges, a cannon comprising traction wheels mounted on said spaced rails, extensions on said cannon depending below the flanges of said rails, rollers rotatively mounted on said extensions disposed below said flanges for retaining said cannon wheels on said rails, brake shoes on said cannon depending below said rails, a plurality of spaced apart adjustable braking devices slidably mounted on the flanges of said rails, each comprising a bar disposed substantially parallel to said rails disposed below the upper surface thereof, and operating mechanism for said slidably mounted bars comprising a common operating lever pivotally mounted on said rails and operatively connected with each of said bars adapted to adjustably position the same for varying the impediment of said cannon as the latter passes over said bars.

In testimony whereof I have affixed my signature.

ANDREW STEINBERGER.
